UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

AUTOMATIC MULTIPLE PLATE-CASTING MACHINE.

Application filed November 9, 1922, Serial No. 599,745. Renewed February 18, 1928.

This invention relates to a machine for casting stereotype printing plates of the curved variety. I have illustrated this invention in a form in which it embodies certain features shown, described and claimed in my co-pending application for patent, Serial Nos. 568,137 and 574,377, filed respectively on the 14th day of June and the 12th day of July, 1922.

The principal objects of the present invention are to apply to the latter of said two devices means for continuously operating the mechanism for controlling the core and keeping it under automatic movement; to provide means for automatically closing the mold, pumping the metal into it, causing the necessary pauses for the casting and cooling and the half rotation for delivery, opening the mold and sawing the ends of the casting; to provide a back member in two parts, each carrying a matrix and capable of being rotated either separately or together, said backs being capable of carrying a single double truck matrix and when so acting capable of casting a double width plate; to provide automatic mechanism for turning the two backs separately or together to bring them into casting position, holding the same stationary during the casting operation and moving them back for the stripping of the matrix or matrices and the delivery of the resulting plate or plates; to provide means by which the machine can be timed to maintain a given rate of production so that no manual work need be done in connection with its operation except to remove the cast plates and risers when they are automatically delivered and to replace old matrices with new ones whenever needed; also to provide automatic means whereby the pump will be operated without the necessity of supervision but under such control that the man can arrest the operation of the pump by hand operated means whenever desirable; to provide means for quadrupling the output of the previous machines of this general type without increasing their floor space or materially increasing the labor required to operate them; and to combine the features shown in my above mentioned applications and render the several operations automatic.

The invention also involves improvements in the features of construction and in the combinations of parts affecting the above results.

Reference is to be had to the accompanying drawings, in which

Figs. 33, 34, 35 and 36 are diagrammatic views showing the operation of the machine.

I have shown the invention as applied to 10 a machine or mold for casting curved stereotype printing plates in which machine the core is mounted to rotate on a fixed vertical axis to cooperate with a semi-cylindrical vertical back movable laterally toward and from 15 the core to complete the mold and open it. Although this invention is capable of being used in other ways, I have shown it as being provided with a core, saws, and back such as shown and described in my co-pending applications 20 above mentioned. The core is rotated half a revolution to deliver the semi-cylindrical cast plate in a vertical position.

The main frame 10 has a hollow support 11 for the bottom of a vertical column 12. On 25 this column is rotatably mounted the rotary core or cylinder 13. This core is cooled by introducing water through a passage 14 into the bottom of a central stationary tube 15 perforated at 16 throughout one half of its 30 circumference and from end to end of the casting chamber. The perforations are used to spray water on the interior surface of the core which is located on the side on which the casting is to be made. The core turns but 35 the tube 15 does not. The water escapes through a hollow base 17 having an outlet. I have shown the device as located adjacent to the usual melting pot 19. The core as will appear cooperates with a double back 48.

The power for the machine is provided 40 through a driving shaft 20 which by means of a worm 21 drives a vertical shaft 22 having a gear connection 23 to a horizontal shaft 24 at the top of the machine. This shaft is in 45 two parts connected by a breaking pin 25. The shaft 24 is provided with a clutch 26 for connecting it with a separate shaft 29 in alignment therewith. A bevel gear 27 on the shaft 29 meshes with a bevel gear 28 fixed to 50 the core 13 for driving it.

A lever 30 is pivoted on a stud 31 for operating the clutch. The lever has a link 38 provided with a yoke 32 entering a groove 33 in the sliding portion of the clutch for connecting and disconnecting the latter. A spring 34 normally holds the lever in a position for disconnecting the clutch. A cam wheel 35 fixed on the core 13 acts on a roller 36 on the lever 30 to hold the clutch engaged 55 throughout half of a revolution of the core. This wheel 35 has two notches 37 into either of which the roller 36 is pressed by the action of the spring 34 at the end of a half revolution. This draws out the clutch and stops 60 the core without interfering with the opera-

tion of the rest of the machine. This provides for rotating the core or cylinder 13 through a half revolution and then automatically stopping it according to said applications.

It has been stated that one of the important features of this invention is to provide automatic means for controlling the various operations. For this purpose, the driving shaft 20 is connected by a worm and worm gear 21 and 121 with a horizontal shaft 122. This shaft through a worm 123 and worm gear 124 drives a cam shaft 125. On this cam shaft there are four cams, a clutch cam 126, a carriage cam 151, a saw cam 149 and a pump cam 170. These are all fixed to the shaft and, of course, in accordance with the gearing, rotate once for each half rotation of the core.

The clutch cam 126 is provided with an internal cam surface having a projection 127 which constitutes its operating means and works once for a short time during each revolution. Extending up from the bearing which supports one end of the shaft 125 is a fixed arm 128 which carries at its end a lever 129. One end of this lever has a roll 130 around which the cam 126 travels and which is moved downwardly once during each rotation by the projection 127. The other end of this lever 129 is connected to a link 131 which operates the yoke 32 connected with the link 38 which operates the clutch 26. This clutch will be closed automatically by the projection 127 at a definite point in the rotation of the shaft 125. After closing, the clutch will remain closed until opened by the spring 34 which normally tends to open it all the time and which is allowed to act when either one of the notches 37 comes into position to receive the roll 36. Then the clutch will open and stay open until operated again by the projection 127. This provides for the automatic rotation of the core a half revolution, its automatic stopping at that time and starting up again without the attention of the operator.

On the shaft 20 there is a gear 40 which, through another gear 39, operates a vertical shaft 41 constantly. This shaft is shown as 115 in two parts each provided with a pulley 42 which, by means of a belt 43 passing over idlers 44, positively rotates a vertical shaft 45 located in bearings on brackets 46 on the frame 10. These two brackets 46 are pivoted 120 on a stationary shaft 47 so that they can swing. On the two shafts 45 are mounted four saws 49, 49^a, 49^b and 49^c located at the proper distance apart to bevel and trim the curved edges of the two plates while on the 125 core and separate the riser.

The saw cam 149 has a cam groove which operates on a roller 140 located on a lever 141 that is pivoted at 142 to swing on its pivot. The upper end of this lever is moved back 130

and forth obviously and is connected by a link 143 with one of the pivoted brackets 46. These brackets are pivoted on the shaft 47 but they are intended to operate together and for that purpose a stud 146 is provided connecting them.

The two parts of the shaft 41 are connected to each other in alignment by a collar 147 slidable on the shaft. The collar has screws 148 for engaging flat surfaces 145 on the two parts of the shaft. When the collar is allowed to drop down to its normal position shown in Fig. 4 it will connect these parts together so that they will rotate absolutely in unison. When it is desired to introduce the lower belt 43, this collar 147 is raised to the dotted line position in Fig. 4 and then the belt can be slipped in edgewise between the adjacent ends of the two parts of the shaft 41. The cam 149 actuates these brackets 46 to move the saws between the two positions shown in Fig. 36 and to bring them into the dot and dash line position shown therein at the time when the mold is open and the cylinder 13 is about to deliver the casting.

Extending out from the frame 10 in a radial direction with respect to the core is a platform 61 having two flat surfaces 62 at its sides constituting tracks. On these tracks run rollers 63 which are mounted on and support the slide 64 carrying the double back 48. The frame 10 is provided with adjustable guides 65 which bear against the sides of this slide 64 and prevent its moving sideways and guide the back to proper position to register with the core as described above.

The double back 48 is moved toward and from the core by a horizontal shaft 51. On this shaft are two arms 52 connected by two links 53 with the opposite sides of a slide 64 on which the back 48 is mounted. The turning of the arms 52 through a short arc results in drawing the slide 64 and back 48 away from the core to the full line position of the back 48 in Fig. 34. This is all that is necessary in the ordinary operation of the device to separate the mold parts prior to delivery of the casting.

The carriage cam 151 operates a roller 152 on a lever 153 pivoted at 54 and therefore reciprocates a link 55 connected with the outer end of this lever. This link is arranged horizontally as shown and its further end connected with an arm 56 which is pivotally mounted on the shaft 51 and is free to swing thereon. It will be obvious from the showing of the extreme positions in full and dotted lines in Fig. 28 that this arm 56 merely oscillates and does not rotate. On the shaft 51 is a double clutch 57. When this clutch is moved to the right hand position shown in Fig. 29, it clutches the shaft 51 to the arm 56 and this shaft oscillates with the arm. This is the ordinary operation and it results in drawing the carriage back at each

half rotation of the core to the full line position shown in Fig. 34 to open the mold and permit the plate to move out of the back by the half rotation of the core. Then the back moves toward the core again automatically by the completion of the other half of the oscillation of this arm 56.

The clutch 57 is operated through a lever 58, link 59 and hand lever 60. It is the right hand position of this lever 60 indicated in dotted lines in Fig. 29 which has just been described. The shaft 41 through bevel gears 98 drives a shaft 94 which through gears 89 drives a horizontal shaft 100. On the shaft 100 is a worm 161 meshing with a worm gear 162 loose on the shaft 51. If the clutch collar 57 is moved to the left in Fig. 29 by moving the lever 60 over to the left hand dotted line position it will clutch the shaft 51 to this gear 162 and cause the shaft 51 to be rotated by power from the rotating shaft 100.

On the end of the shaft 51 is a disc 163 having two teeth 164 and 165 oppositely located thereon each provided with a slanting rear surface and an abrupt front surface and one of them being twice as high as the other. This disc is fixed to the shaft to rotate with it and when the lever 60 is moved over to the position to clutch the shaft to the positively and constantly driven worm 161, a projection 166 on the lever will be located up against the edge of the disc in the path of the two projections 164 and 165. These are so located that after the shaft 51 has rotated half a revolution, which it does while the shaft 125 is also rotating a half revolution, the smaller projection 164 will engage the projection 166 and move the lever 60 back to the neutral position shown in full lines. The result of this is to move the slide 64 back to the dotted line position shown in Fig. 34 to permit of the removal, exchange or replacement of the matrix or matrices.

At this time the carriage 64 is left in stationary position, not being acted on by either the oscillating or the rotating mechanism and it will not be started up in any way until the operator moves the lever 60. When he has got the new matrix or matrices properly located in the back he swings the lever 60 back to the left behind the small projection 164. That causes the shaft 51 to be positively turned through a half a revolution in order to bring the back up to the position shown in Fig. 35 ready for casting. When that motion is completed the long projection 165 strikes the projection 166 and moves the lever 60 clear over to the right to the dotted line position shown there. This forces the clutch out of engagement with the worm gear 162 through the neutral position shown in full lines in Fig. 29 and over into the right hand position in which it engages the clutch teeth on the hub of the arm 56. Thereafter

the back continues to reciprocate from the position shown in Fig. 35 to the full line position shown in Fig. 34 and back again without further attention.

5 This invention, as stated above, is designed to cast a plurality of printing plates on one side of a core. The mold is prepared with two matrices M and M' located in the back and provided with a T-shaped semi-circular 10 strip 66 located in a curved space 67 in the back and having its flanges projecting into the mold cavity and over the lower edge of the top matrix and the upper edge of the lower matrix, preventing the metal from getting behind them. A pouring sheet S is used at the top, as usual. The bottom of the lower matrix is held in position in any of the ordinary ways.

20 The metal is cast and the back is drawn away. Then the saws 49, 49^a, 49^b and 49^c are brought into position at the edge of the casting automatically. The core is rotated now to the position shown in Fig. 34 exactly opposite to that shown in Fig. 35. During this 25 operation the two lower saws cut and bevel the upper and lower edges of the lower plate P' and the upper two saws perform the same two operations on the upper plate P . Between the saws 49^a and 49^b there is a section 30 which is cut away from the rest of the casting and falls down below when the cast plates are ejected. The saw 49 separates the riser R from the upper plate P . This riser is provided as usual with an enlarged top caused 35 by the beveled upper end of the core or cylinder 13.

40 If it is desired to cast a single plate of double width or the so-called double truck plate, a single matrix M^2 is used with the same pouring sheet and the space 67 is filled by a semi-circular plug or block 68 located behind the matrix so that the pressure of the metal will not bend the matrix at this point. The large double truck plate P^2 is produced and 45 cut by the saws 49 and 49^c so that the riser is separated and the ends of the plate beveled. The saws 49^a and 49^b are removed. The bottom end is beveled by the shape of the mold and the saw 49^c merely trims the edge.

50 This mold will also accomplish a third object, that is, it can cast an ordinary single width plate in the upper position. This is shown in Fig. 18 and is accomplished by substituting for the T-strip 66 or the block 68 a 55 foot ring 69. This also is of T-shape but it extends clear across the mold cavity and holds the matrix in the ordinary manner. There is a difference here in that the bottom of the cast plate P^3 is not beveled by this foot ring but is cast flat. Therefore, the saw 49^a which trims this bottom is employed to cut a bevel on it.

60 The separation of the plate or plates from the core or cylinder is accomplished in any desired way. These plates are pushed out re-

spectively on the upper delivery stand 70 and the lower delivery stand 71 which are located in a position to register with the cylinder 13 and support the plates on their edges. The upper stand is removably mounted by means 70 of bolts so that it can be removed when not needed.

75 The back is provided at each of its side edges with a vertical rock shaft 75. The matrix bar 80 which is mounted on the shaft 75 carries the matrix holding clip 88. One of these clips is provided at each side of the back for the matrix. These clips in the usual way come over the edges of the matrix and on being pulled over clamp the matrix in position against the bar 80.

80 As has been stated, the back 48 is mounted to move toward and from the core both for the purpose of separating the back from the cast plates on the core and for the purpose of drawing the back out far enough to permit of exchange of matrices.

85 The back is of double formation having two semi-cylindrical mold concavities or casting surfaces on opposite sides, each one adapted to hold two matrices in the manner which has been indicated above. Each part is mounted to turn independently on a vertical stationary shaft and support 90 which is mounted on the slide 64 which moves back 90 and forth on the tracks.

90 Extending through this support 90 is a cooling water inlet 89 having two radial ports each located at the bottom of one of the two mold cavities. On opposite sides are two 100 pairs of water cooling passages 91 cast in each part of the back itself. All of these passages are of semi-cylindrical formation, surrounding the semi-cylindrical mold surfaces. Each one is provided with a radial outlet port 105 92 at the top and a radial inlet port at the bottom. The two parts are journaled on each other at the center and their water cooling passages register.

110 The box is also provided with a longitudinal passage 92 for allowing the water to drain out. This passage extends out horizontally at the top to form a radial port so that when the back is swung around the stationary support 90, the port 93 will register at the top with one of the ports 92 and the inlet 89 will register similarly in certain positions. The top of the passage 93 extends toward the core and therefore the water will circulate in the water passages 91 which extend toward the core; that is, the ones which are ready for casting, or are in the act of casting. These casting surfaces are cooled therefore while the opposite ones are not.

115 On the bottom of the back is fixed a gear 95 which is operated by a bevel gear 96 on a transverse shaft 97. A worm and worm wheel 99 drive the shaft 97 from the shaft 100. The worm 99 is slidingly keyed to the shaft and these wheels 99 travel along this 120 125 130

shaft 100 with the back 48. They are always in mesh and always rotating constantly, but the shaft 97 is connected with the worm wheel by a clutch 101 operated by a lever 109 connected by a link 102 with a lever 103 pivoted to it and supported on the slide 64. The other end of the lever is provided with a roll or projection 106 adapted to be engaged normally in either one of two diametrically opposite notches 107 on a disc 110 on the bottom of the rotary back 48 to lock it against rotation. When the clutch is connected, the back is rotating. As soon as the back is rotated half a revolution the roll 106 comes into registration with one of the notches 107 and is forced into it by a spring 108. This disconnects the clutch and stops the rotation.

Many of the above described features are shown in substantially the form illustrated in my above mentioned co-pending applications and claimed therein. Therefore, they are not claimed in this case except as they are changed herein or enter into combination with the novel features described herein.

As stated above, I have shown the machine in a form in which it is capable of casting two plates, a double truck plate, or a single plate of the ordinary size. In order to provide for operating the two halves of the back separately so that the upper and lower one will work together when two plates are being cast or a single plate of double width and so that either one of them can be caused to work alone, if only one single width plate is to be cast I connect the shaft 100 with mechanism at the top for operating the upper half of the back of a similar nature to the mechanism shown in Fig. 15 and just described. For that purpose I have shown a bevel gear 111 on the shaft 100 meshing with a similar gear on a vertical shaft 112. This vertical shaft extends up beyond the top of the back and by bevel gears 113 drives a horizontal shaft 114 similar to the shaft 100 and acting in the same way. This shaft 114 is connected by worm and gear 115 with a horizontal shaft 116 through a clutch 117 operating in the same manner as the clutch 101. For operating this clutch I provide a lever 203 connected with a bell crank 119 which has a pin 118 for actuating the clutch 117. This lever 203 is operated the same way as the lever 103 and co-operates with a ring 120 on the top of the back having notches similar to the notches 107 and having the same functions. The shaft 116 drives the upper half of the back through a gear on the upper end thereof operating like the gear 95 below. It will be understood that the lower gear operates the lower half of the back independently of the upper half but ordinarily the two gears are connected together through the shaft 112 and clutches 101 and 117 so that they operate together. Either one can be thrown into operation by

the lever 103 or 203 independently of the other.

When it is desired to cast a single plate of double width (or a double truck plate) the backs 48, Fig. 7, must be held in alignment while being rotated. To accomplish this, the backs 48 are locked together by pin 197 which passes through lugs 198, one attached to the upper back 48 and the other attached to the lower back 48. When the backs 48 are connected by pin 197 for casting a double truck plate and it is desired to rotate the backs, this rotation is accomplished by operating lever 103, Figs. 13 and 15, at the bottom of the lower back, the mechanism in Fig. 14 being disconnected by withdrawing a pin 199 which connects lever 203 and 119. A cotter pin is used merely to hold pin 199 in place. Being thus disconnected, clutch 117 held out of gear by spring 196 operating through lever 119 and pin 118. Ordinarily the mechanism in Fig. 14 is used to operate rotation of the upper back 48, and the mechanism in Fig. 15 is used to operate rotation of the lower back 48.

Another feature of this invention consists in the automatic control of the pump in the metal pot 19. This is a pump of well known kind employing a cylinder 171, a piston 172 operated by a rod 173 and lever 174. The lever is connected by a link 175 with a lever 176 having a roll 177 operating in a groove in the cam 170. As the cam shaft 125 rotates constantly, the plunger 172 also will operate upwardly each time the core 13 comes to a stop to eject the charge of metal through the spout 178 into the mold. In order to prevent the discharge of metal into the mold space when the mold is not closed in spite of the fact that the piston 172 continues to operate, I make use of a port 179 in the top of the cylinder 171 and a valve 180 for closing the port. This valve normally is closed and the pump operates in the manner above described when it is closed but when the valve 180 is opened the reciprocation of the piston 172 can take place without discharging any metal, because in that case the metal will flow through the port 179 instead of being lifted into and discharged through the spout 178.

For operating the valve 180 I provide the carriage 64 with a frame 181 having a cam 182 thereon. This frame is provided with a hub slidable on the shaft 100 and whenever the carriage 64 moves back to the position shown in full lines in Fig. 34, as it is ordinarily in the casting operation, the cam 182 will move back with it without performing any function. But when the carriage moves back beyond this position in order to get into the dotted line position in Fig. 34 the cam will engage a roll 183 on an arm 184 on a vertical shaft 185. This shaft has at the top an arm 186 connected by a link 187 with a bell crank

188. A spring 189 normally holds the bell crank out of operative position but when the cam moves the roll 183 the bell crank is forced down to engage a collar 190 on the valve stem 191 to force the valve 180 down into open position and prevent the discharge of metal by the pump. This occurs, of course, when the shaft 51 is being rotated by the worm 161.

10. From the diagram shown in Fig. 33 it will be seen that the sequence of operations is such that a plate or set of plates can be cast every fifteen seconds by this machine. Starting at the point marked zero it takes one second 15 to close the mold and then one and a half seconds to pump the metal into it. The parts then continue to operate for ten seconds while the casting is being cooled. It then takes one second to open the mold and then one and one 20 half seconds to swing the core around and bring the plate into position for discharging and to saw the riser off and trim the ends of the plates. The total time consumed is fifteen seconds for a cast or set of two casts.

25. The operation will be understood from what has been stated and particularly from an inspection of the diagrammatic views on the last sheet of drawings. It will be seen from what has been stated that this invention 30 can be applied to a machine having a back member of two parts, each carrying a matrix capable of being rotated either automatically together or one of them singly and that the two parts are capable of carrying a 35 single or double page matrix for casting a double width plate, and that the opening and closing of the casting box is also done entirely automatically and without the interposition of any hand operation. The operator 40 does not have to control the action of the machine unless he wishes to move out the back to change the matrix. Otherwise it will go through the sequence of operations indicated in Fig. 33 over and over in an entirely automatic 45 manner. The machine can be timed to maintain a good rate of production and no hand work need be done in connection with its operation except to remove the plates and risers when they are delivered and to replace 50 the old matrices with new ones. The pump also operates automatically and its control also is automatic as stated to prevent discharging metal when the mold is open. This permits of a very material increase in the output 55 of the stereotype machines now known without increasing the floor space or materially increasing the labor used to operate them.

60. Although I have illustrated and described only a single form of the invention, I am aware of the fact that modifications can be made therein by any person skilled in the art without departing from the scope of the invention as expressed in the claims.

Therefore, I do not wish to be limited to all

the details of construction herein shown and 65 described but what I do claim is:—

1. In a stereotype printing plate mold, the combination with a core, of a back co-operating therewith and having a length sufficient to receive two stereotype printing plate matrices therein in alignment, said back consisting of two parts in axial alignment, each rotatable independently of the other.

2. In a stereotype printing plate mold, the combination with a core, of a back co-operating therewith and having a length sufficient to receive two stereotype printing plate matrices therein in alignment, said back consisting of two parts in axial alignment, one rotatable independently of the other, and means for rotating one part of the back independently of the other.

3. In a stereotype printing plate mold, the combination with a core, of a back co-operating therewith and having a length sufficient to receive two stereotype printing plate matrices therein in alignment, said back consisting of two parts in axial alignment, each rotatable independently of the other, means for rotating one part of the back independently of the other, and means for connecting the two rotating means to cause the two parts to rotate in unison.

4. In a multiple stereotype plate casting machine, the combination with a core rotatable on an axis for delivering a casting out of the mold, and a back cooperating therewith and consisting of two parts, of a non-rotatable shaft on which both parts of said back are independently rotatable, means for moving said back away from the core, means whereby when the back is moved to its limiting position both parts of the back will be connected with a source of power and rotated, and means for automatically stopping the rotation of each part of the back independently when it has completed a half revolution.

5. In a multiple stereotype plate casting machine, the combination with a core and a back cooperating therewith and consisting of two parts, of a non-rotatable shaft on which both parts of said back are independently rotatable, means whereby both parts of the back will be connected with a source of power and rotated, and means for automatically stopping the rotation of each part of the back independently when it has completed a half revolution, each of the last named means being capable of being thrown out of action manually.

6. In a multiple casting machine, the combination with a core and a back consisting of a plurality of parts in axial alignment each adapted to receive an independent matrix and each adapted to cooperate with the core, of a non-rotatable shaft on which both parts of said back are rotatably mounted,

means for moving said back away from the core, a bottom and a top shaft each connected with one of the parts of the back for rotating it, a clutch on each shaft, a shaft 5 for connecting said clutches, means whereby when the back is moved back one of the first named shafts will be connected with a source of power and rotated, and independent means for operating the two clutches.

10. 7. In a mold for casting a plurality of stereotype printing plates, the combination of a convex core and a back comprising a plurality of parts each having a casting surface thereon for cooperating with the core, 15 with means on which each part of the back is adapted to turn independently, one part of the back being journaled on the other, means for introducing water for cooling purposes into the interior of one of said parts behind 20 its casting surface, and means extending through said part for allowing the water to circulate into the other part behind the casting surface thereof.

8. In a multiple stereotype plate casting machine, the combination with a core rotatable on an axis for delivering a casting out of the mold, and a back cooperating therewith and consisting of two parts, of a non-rotatable shaft on which both parts of said 25 back are independently rotatable, means for moving said back away from the core, means whereby when the back is moved to its limiting position both parts of the back will be connected with a source of power and rotated, 30 means for automatically stopping the rotation of each part of the back independently when it has completed a half revolution, a set of constantly rotating saws, and means for automatically moving said saws toward the core to cut into the cast when the core 35 rotates to deliver it.

9. In a mold for casting a stereotype printing plate, the combination with a back, of a rotatably mounted core adapted to cooperate therewith, a constantly driven shaft, a clutch for connecting the shaft with the core for rotating the core, means rotatable in unison with said shaft for automatically throwing in said clutch at a definite point 40 in the rotation of said shaft, a saw mounted to move toward and from the core and means mounted to rotate with said shaft for automatically moving the saw toward the core to cut into the cast when the clutch is thrown in.

10. In a curved stereotype plate casting machine, the combination with a curved back and a shaft, of a core, a clutch for connecting said shaft with the core for rotating it, a cam shaft connected with said shaft to rotate therewith, a cam on said shaft, a roll operating on said cam, a lever for throwing the clutch, means connected with and operated by the roll for operating said lever to throw the clutch in, a set of saws mounted

to move bodily toward the core to enter a cast thereon, means for rotating said saws constantly, and means connected with said saws to move them toward the core when the clutch is thrown in.

11. The combination with a mold for casting a curved stereotype printing plate, of a set of saws arranged to move together toward and from the casting device into a position to cut into the casting as it is ejected from the mold and trim the curved edges of the plate, a cam shaft, a cam on the cam shaft for automatically controlling the opening and closing of the mold, a saw cam on said shaft, and means operated by said saw cam for moving the saws into operative position automatically and periodically.

12. In a stereotype plate casting machine, the combination of a core adapted to turn to deliver the casting, a segmental back, and a sliding frame on which said back is mounted, with a shaft connected with said frame for moving the back toward and from the core, a cam shaft, a cam on the cam shaft for controlling the operation of the first named shaft, saws for operating on the cast plate while located on the core, and a cam on said cam shaft having connections for moving said saws toward the core as the back starts to move away.

13. In a curved stereotype plate casting machine, the combination with a curved back and a shaft, of a core, a clutch for connecting said shaft with the core for rotating it, a cam shaft connected with said shaft to rotate therewith, a cam on said shaft, a roll operating on said cam, a lever for throwing the clutch, means connected with and operated by the roll for operating said lever to throw the clutch in, a set of saws mounted to move bodily toward the core to enter a cast thereon, means for rotating said saws constantly, a second cam on the cam shaft connected with said saws to move them toward the core when the clutch is thrown in, and a third cam on said cam shaft connected to draw the back away from the core just before the core turning cam starts to turn the core to deliver a cast.

14. In a mold for casting a curved stereotype printing plate, the combination with a back, of a rotatably mounted core adapted to cooperate therewith, a constantly driven shaft, a clutch for connecting the shaft with the core for rotating the core, means rotatable in unison with said shaft for automatically throwing in said clutch at a definite point in the rotation of said shaft, a saw mounted to move toward and from the core, means mounted to rotate with said shaft for automatically moving the saw toward the core to cut into the cast when the clutch is thrown in, and means operated by said shaft for periodically and automatically separating the back from the core.

15. In a curved stereotype plate casting mold, the combination with a cylindrical core and a double semi-cylindrical back, of means for periodically, automatically and repeatedly separating the back from the core, means for disconnecting the back from the separating means, and means adapted to be operated by the separating means for turning the back around to present the other part of it to the core. 70
16. In a stereotype plate casting mold, the combination with a core and a back having two concave casting faces oppositely located thereon, of means for repeatedly separating the back and core, manual means for disconnecting the back from the separating means, and means controlled by said manual means for automatically turning the back exactly half way around when the mold parts are separated. 75
17. In a stereotype casting mold, the combination of two mold parts adapted to form a complete mold when brought together, one of said parts being adapted to carry a casting matrix, means for repeatedly moving the latter part directly away from the other for freeing the casting and returning it to casting position automatically, automatic means for moving said part in another direction for exposing its inside casting surface and allowing the convenient inspection or exchange of its matrix, and manually controlled means for connecting either of said means with a source of power but not both at the same time. 80
18. In a curved stereotype plate casting mold, the combination with a convex core adapted to have a plurality of plates cast on different faces thereof, of a back having a plurality of concave casting surfaces each adapted to carry a matrix and to cooperate with one of said surfaces of the core, means for moving the back toward and from the core to close and open the core automatically as long as desired, means for moving said back further from the core to permit inspection of the matrix, a shaft for operating each of the last two means, a clutch for connecting either of said means with the shaft, means for turning the back to bring another of said casting surfaces thereon into registration with the core to complete the mold, and automatic means for operating the last two named means. 85
19. In a stereotype plate casting mold, the combination with a core, means for moving said core for delivering a cast plate, and a back for co-operating with the core, of means for drawing the back away from the core and returning it automatically to open and close the mold, means for moving the back to a point beyond the ordinary open delivering position, a hand lever, and means operated by the hand lever for connecting the back with either of said means at will. 90
20. In a stereotype plate casting mold, the combination with a core, means for moving said core for delivering a cast plate, and a back having a plurality of casting surfaces for co-operating with the core, of means for drawing the back away from the core and returning it automatically to open and close the mold, means for moving the back to a point beyond the ordinary open delivering position and turning the back automatically through a predetermined angle to bring another face of said back into registration with the core, a hand lever, and means operated by the hand lever for connecting the back with either of said means at will. 95
21. In a stereotype plate casting machine, the combination with a core and a reciprocable back, of a shaft, means on said shaft connected with said back for reciprocating it, a cam shaft, a cam on the cam shaft, means for connecting said cam for operating said means as the cam rotates, a gear loose on the first named shaft, means for rotating said gear constantly, and means for clutching the shaft to the gear so as to rotate said shaft and reciprocate the back through a longer path of travel. 100
22. In a stereotype plate casting machine, the combination with a core and a reciprocable back, a shaft, an arm loose on said shaft connected with said back for reciprocating it, a cam shaft, a cam on the cam shaft, means for connecting said cam with said arm for oscillating the arm as the cam rotates, a clutch on the first named shaft, manual means for connecting said clutch with the arm for causing the shaft to oscillate and the back to reciprocate, a gear loose on the first named shaft, means for rotating said gear constantly, and means for clutching the shaft to the gear so as to rotate said shaft and reciprocate the back through a longer path of travel. 105
23. In a stereotype plate casting machine, the combination with a core, of a back, a shaft, an arm loose on said shaft connected with said back for reciprocating it, means for connecting said arm with a source of power for oscillating the arm, a clutch on the shaft, a gear loose on the shaft, means for rotating said gear constantly, said clutch having two faces and movable to three positions in one of which it is neutral and the shaft is disconnected from the power, and in the others of which it connects the shaft either with the arm to oscillate or with the gear to rotate, whereby the shaft cannot be connected with the gear and the arm at the same time. 110
24. In a stereotype plate casting machine, the combination with a core, of a back for co-operating therewith, said back being movable toward and from the core, a shaft, means for connecting the shaft with the back to reciprocate the back from the shaft, means for oscillating said shaft adapted to be connected 115
- 120
- 125
- 130

therewith and disconnected therefrom, means for rotating said shaft adapted to be connected therewith and disconnected therefrom, a clutch for connecting either the oscillating or the rotating means with the shaft but not both at the same time, a lever for operating said clutch, whereby when the lever is in neutral position the back will not move, when the lever is in one extreme position the back will be reciprocated through a short path for opening and closing the mold, and when the lever is in the opposite extreme position the back will be reciprocated through a longer path so as to draw it a distance away from the mold to permit inspection and replacement of the matrix.

25. In a stereotype plate casting machine, the combination with a core, of a back, a shaft, means for connecting the shaft with the back to reciprocate the back from the shaft, means for oscillating said shaft, means for rotating said shaft, a clutch for connecting either the oscillating or the rotating means with the shaft, a manually-controlled lever for operating said clutch, whereby when the lever is in neutral position the back will not move, when the lever is in one extreme position the back will be reciprocated through a short path, and when the lever is in the opposite extreme position the back will be reciprocated through a longer path, and means for automatically disconnecting the rotating means from the back after the back has been drawn away to the limit of its reciprocation.

26. In a stereotype plate casting machine, the combination with a core, of a back for cooperating therewith, said back being movable toward and from the core, a shaft, means for connecting the shaft with the back to reciprocate the back from the shaft, means for oscillating said shaft, means for rotating said shaft, a clutch for connecting either the oscillating or the rotating means with the shaft, means whereby the back can be prevented from moving, or will be reciprocated through a short path for opening and closing the mold, or reciprocated through a longer path so as to draw it away from the mold to permit inspection and replacement of the matrix, means for automatically disconnecting the rotating means from the back when the back has been drawn away to the limit of its reciprocation, and means for rotating the back a half revolution automatically when again connected with the rotary means.

27. In a stereotype plate casting machine, the combination with a core, of a back, a shaft, means for connecting the shaft with the back to reciprocate the back from the shaft, means for oscillating said shaft, means for rotating said shaft, a clutch for connecting either the oscillating or the rotating means with the shaft, a manually-controlled lever for operating said clutch, whereby when the lever is in

neutral position the back will not move, when the lever is in one extreme position the back will be reciprocated through a short path, and when the lever is in the opposite extreme position the back will be reciprocated through a longer path, and a disc on said shaft having two opposite teeth thereon, the lever having a tooth in position to be engaged by one of said teeth upon the completion of half a revolution to move the lever away from its position for connecting the shaft with the rotating means operative when the back has been moved to the limit of its reciprocation.

28. In a stereotype plate casting machine, the combination with a core, of a back, a shaft, means for connecting the shaft with the back to reciprocate the back from the shaft, means for oscillating said shaft, means for rotating said shaft, a clutch for connecting either the oscillating or the rotating means with the shaft, a manually-controlled lever for operating said clutch, a disc on said shaft having two opposite teeth thereon, one longer than the other, the lever having a tooth adapted to be engaged first by one of said teeth and then by the other each after a half revolution to move it from a position for connecting the shaft with the rotating means, the short tooth being just long enough to return the lever to neutral position, and the long one being long enough to return the lever to the opposite extreme position and clutch the shaft to its oscillating means.

29. In a stereotype plate casting machine, the combination with a core and a reciprocable back, of a shaft for reciprocating the back, separate means for oscillating and rotating said shaft, a clutch for connecting the shaft with either the rotating or the oscillating means, a lever for controlling the clutch having a tooth on it, and a disc on the shaft having two opposite teeth of different lengths for engaging said tooth, one of them being adapted to return the lever to neutral position and the other to return it to its opposite extreme position to clutch the shaft to the oscillating means, whereby when the lever is operated to connect the shaft with the rotating means the shaft will be rotated half a revolution and the back will be drawn away from the mold to its extreme position and then the clutch will be moved to disconnect the shaft from the power to permit of inspection and exchange of matrices, and whereby if the lever is again moved to connect the clutch with the rotating means a second half revolution of the shaft will cause the back to be returned to casting position and the lever to be thrown over into its opposite extreme position to clutch the shaft to the oscillating means, whereby the back will then be connected with the means for opening and closing it automatically.

30. In a stereotype plate casting machine, the combination with a core, of a concave back, a slide on which said back is mounted, a

shaft, an arm loose on said shaft connected with said slide for reciprocating it, a cam shaft, a cam on the cam shaft, means for connecting said cam with said arm for oscillating the arm as the cam rotates, a clutch on the first named shaft, manual means for connecting said clutch with the arm for causing the shaft to oscillate and the slide to reciprocate, and another cam on the cam shaft having connections for rotating the core a revolution to each full reciprocation of the slide.

31. In a stereotype plate casting machine, the combination with a core, of a concave back, a slide on which said back is mounted, a shaft, an arm loose on said shaft connected with said slide for reciprocating it, a cam shaft, a cam on the cam shaft, means for connecting said cam with said arm for oscillating the arm as the cam rotates, a clutch, means for connecting said clutch with the arm for causing the shaft to oscillate and the slide to reciprocate, another cam on the cam shaft having connections for rotating the core a half revolution, a third cam on the cam shaft, a pump for introducing metal into the mold, means on said pump for rendering it inoperative, means on the cam shaft for operating the pump constantly, and means movable with the slide for rendering the pump inoperative when the back is moved to its extreme retracted position.

32. In a stereotype plate casting machine, the combination with a core, of a back, a shaft, means for connecting the shaft with the back to reciprocate the back from the shaft, means for oscillating said shaft, a clutch for connecting the oscillating means with the shaft, a lever for operating said clutch, whereby when the lever is in neutral position the back will not move and when the lever is in one extreme position the back will be reciprocated through a short path for opening and closing the mold, a metal pump for introducing metal into the mold, means for constantly operating the piston of said pump, a cam operating with said back, a lever having its end in a position to be engaged and operated by said cam when the back is retracted to its extreme position, and means connected with said lever for rendering said pump inoperative in spite of the continuous operation of its piston as long as the back remains in said position.

33. In a stereotype plate casting machine, the combination with a core, of a back, a shaft, means for connecting the shaft with the back to reciprocate the back from the shaft, means for oscillating said shaft, means for rotating said shaft, a clutch for connecting either the oscillating or the rotating means with the shaft, a manually-controlled lever for operating said clutch, whereby when the lever is in neutral position the back will not move, when the lever is in one extreme position the back will be reciprocated

through a short path for opening and closing the mold, and when the lever is in the opposite extreme position the back will be reciprocated through a longer path so as to draw it away from the mold, a metal pump for introducing metal into the mold, means for constantly operating the piston of said pump, a cam operating with said back, a lever having its end in a position to be engaged and operated by said cam when the back is retracted to its extreme position by said rotating means, and means connected with said lever for rendering said pump inoperative in spite of the continuous operation of its piston as long as the back remains in said position.

34. In a stereotype plate casting machine, the combination with a core, a back, and a pump, of means for automatically moving the back against the core, means cooperating therewith for then automatically operating the back moving means to draw the back away from the core, means for automatically operating the pump to fill the mold, means for automatically turning the core a half revolution timed to operate as soon as the back moves away to deliver the cast plate, constantly rotating saws, and means timed to operate when the core starts to turn for moving the saws into a position to saw through the plate as it turns on the core.

35. The combination with a mold for casting a curved stereotype printing plate, of a set of saws arranged to move together toward and from the casting device into a position to cut into the casting while it is being ejected from the mold and trim the curved edges of the plate, means for automatically controlling the opening and closing of the mold, and means for moving the saws into operative position automatically and periodically.

36. In a stereotype plate casting machine, the combination of a core adapted to turn to deliver the casting, a segmental back, and a sliding frame on which said back is mounted, with a shaft connected with said frame for moving the back toward and from the core, a cam shaft, a cam on the cam shaft for controlling the operation of the first named shaft, saws for operating on the cast plate while located on the core, and means for moving said saws toward the core as the back starts to move away.

37. In a curved stereotype plate casting machine, the combination with a curved back and a shaft, of a core, a clutch for connecting said shaft with the core for rotating it, a cam shaft connected with said shaft to rotate therewith, a cam on said shaft, a roll operating on said cam, a lever for throwing the clutch, means connected with and operated by the roll for operating said lever to throw the clutch in, a set of saws mounted to move bodily toward the core to enter a cast thereon, means for rotating said saws

constantly, means connected with said saws to move them toward the core when the clutch is thrown in, and means connected to draw the back away from the core just before the 5 core turning cam starts to turn the core to deliver a cast.

38. In an apparatus for casting stereotype printing plates, the combination with a back, of a plurality of matrix-holding supports or surfaces carried thereby, each of 10 which is adapted to be interchangeably brought into the same casting position.

39. In an apparatus for casting stereo-

type printing plates, the combination of a core member, a pivotally or rotatably mounted back, means for supporting a plurality of matrices in the back, and means whereby the back may be turned about a pivot in order that each matrix may interchangeably be presented to or brought into cooperative 15 relation with the core member to form a casting mold.

In testimony whereof I have hereunto affixed my signature.

HENRY A. WISE WOOD.
